UNITED STATES PATENT OFFICE.

ALVA J. FISHER, OF EVANSTON, ILLINOIS, ASSIGNEE TO HURLEY MACHINE COMPANY,
OF CHICAGO, ILLINOIS, A CORPORATION OF ILLINOIS.

CLERK'S-WEINGART.

1,136,221.

Specification of Letters Patent. Patented Apr. 20, 1915.

Application filed June 8, 1914. Serial No. 342,781.

To all whom it may concern:

Be it known that I, ALVA J. FISHER, a citizen of the United States, residing at Evanston, in the county of Cook and State of Illinois, have invented certain new and useful Improvements in Clothes-Wringers, of which the following is a specification.

My invention relates to clothes wringers, more particularly those of the power-driven type and the object thereof is to provide a wringer with novel and efficient mechanism acting as a guard for the rollers of the wringer to prevent the catching of the fingers of the operator between the rollers and thereby avoiding injury. My attachment or guard is so made as to not only efficiently secure the result named but also so as not to interfere with the functions of the wringer.

20 The various features of advantage and utility in my attachment will be made apparent by the description hereinafter given.

In the drawing, Figure 1 is a side elevation of a wringer embodying my invention and Fig. 2 an end view thereof with a portion broken away to expose the wringer rolls.

Referring to the present embodiment of my invention as herein shown the wringer itself may be of the usual and well-known construction, the one herein shown being driven by power. This wringer comprises the usual frame consisting of the end members or standards 1, the top cross bar 2, the cross-board 3, the upper and lower wringer 35 rolls 4 and 5 journaled in the studs and connected at their ends by the usual gearing (not shown) inclosed in the case 6, the lower roll being driven by power applied to the left-hand end of Fig. 1 thereof. The 40 wringer is attached in any suitable manner to the side of the tub 7 or on any other support.

There are two guards for the wringer rolls 1 on each side thereof and the construction 45 of the same with their operating parts is exactly the same but they are so arranged that when one is in operative position the other is in inoperative position so far as the guard function is concerned, the alternating 50 position of the guards taking place automatically as hereinafter explained. In view of the similarity between the guards and their associated parts the same reference figures will be applied to both.

55 Upon each side of the wringer frame, in

the present instance upon one side of the vertical standards 1, is pivoted a pair of guide rods 8 having their upper ends bent at right angles and arranged to oscillate in bearings 9 secured to said standards. These 60 guide rods depend from these bearings and are positioned parallel to the standards near their inner sides as shown in Fig. 1. Upon each pair of guide rods a guard in the form of a plate 10 is mounted to slide in 65 a substantially vertical position and longitudinally of the guide rods. To this end the corners of the guard plate are provided with outwardly-projecting lugs 11 having vertical holes through which the guide rods 70 8 loosely pass. In order to limit the downward movement of the guard plate on the rods the latter are provided with pins 12 below the lower lugs 11. The guard plate is provided toward its lower end with a 75 longitudinal or horizontal slot 10^a which when the guard is in the operative position shown at the right-hand side of Fig. 2 registers with the bite of the roll, that is, is in the same horizontal position as the line 80 of contact between the two wringer rolls with the result that the clothes when passed through the slot will be immediately engaged and drawn in by the rolls.

A drip board 13 is pivoted by means of 85 end studs or bearings 14 between the vertical standards 1 of the wringer and is arranged to tilt or oscillate as shown by the full and dotted-line positions of Fig. 2. This drip board is operatively connected 90 with the two guards in such manner so that when the drip board is in one position one of the guards is in operative position so far as the wringer function is concerned and the other is in inoperative position and out 95 of the way of the discharge of the clothes by the wringer rolls. To this end, the outer ends of the drip board are operatively connected with the lower ends of links 15, here in the form of rods whose ends are inwardly turned. The upper ends of these rods are loosely received in transverse holes in the upper lugs 11 and the lower ends thereof are loosely received in elongated openings 13^a of the drip plate. By reason of this connection the alternate positions of the two guards are determined and the positioning of such guards is automatically given and determined by the movements of the drip 105 board.

When the guard plate on the right-hand side of Fig. 2 is in its operative position as shown in full lines, the clothes are fed from that side and through the wringer rolls. At 5 this time the other guard is in inoperative position as shown in full lines on the left-hand side of Fig. 2 and its position is such that it does not interfere with the delivery of the clothes from the wringer rolls. It 10 will be understood that if this latter guard should have remained in its other position which is shown in dotted lines on the left-hand side of Fig. 2 it would have materially interfered with such delivery. When it is 15 desired to pass the clothes through the wringer from the other side, that is from the left-hand side of Fig. 2, the direction of rotation of the wringer rolls having been reversed, the drip board is oscillated to the 20 dotted-line position whereupon the left-hand guard assumes the position shown in dotted lines while the right-hand guard is moved from the full line position to the dotted line position of Fig. 2. By means of my guards 25 I accomplish the double purpose of guarding the wringer rolls and of preventing any interference or obstruction to the delivery of the clothes by the particular guard which is not being used for guard purposes at the 30 particular time.

I claim:

1. In combination with a clothes wringer including its rolls, guards located on opposite sides of the rolls and arranged to swing 35 toward and away therefrom, and connections between the guards for alternately presenting the guards to the rolls for guarding purposes.

2. In combination with a clothes wringer 40 including its rolls, guards located on opposite sides of the rolls and arranged to swing toward and away therefrom, and an oscillating drip board operatively connected at its opposite ends to the guards whereby as 45 one of the guards is presented to the rolls the other is swung away therefrom.

3. In combination with a clothes wringer including its rolls, guards located on opposite sides of the rolls, guide rods which are 50 arranged to oscillate on the wringer and on which the guards are mounted, and connections between the guards for alternately presenting the guards to the rolls for guarding purposes.

4. In combination with a clothes wringer 55 including its rolls, guards located on opposite sides of the rolls, guide rods which are arranged to oscillate on the wringer and on which the guards are carried and are also mounted to slide longitudinally of the guide 60 rods, and connections between the guards for alternately presenting the guards to the rolls for guarding purposes.

5. In combination with a clothes wringer 65 including its rolls, guards located on opposite sides of the rolls, guide rods which are arranged to oscillate on the wringer and on which the guards are carried and are also mounted to slide longitudinally of the guide 70 rods, and an oscillating drip board operatively connected at its opposite ends to the guards.

6. In combination with a clothes wringer including its rolls, guards located on opposite sides of the rolls, and in the form of 75 two plates each having a horizontal slot and a series of apertured lugs, guide rods arranged to oscillate on the wringer and passing loosely through the apertures of the lugs, and connections between the two plates for 80 alternately presenting the guards to the rolls for guarding purposes.

7. In combination with a clothes wringer including its rolls, guards located on opposite sides of the rolls, and in the form of 85 two plates each having a horizontal slot and a series of apertured lugs, guide rods arranged to oscillate on the wringer and passing loosely through the apertures of the lugs, an oscillating drip board, and pairs 90 of links pivotally connected at one end to the opposite ends of the board and at the other end to the guards.

8. In combination with a clothes wringer including its rolls, guards 10 arranged on 95 opposite sides of the rolls and each having a slot 10^a and pairs of outwardly extending lugs 11 at its upper and lower corners, a drip board arranged to oscillate on the wringer below its rolls, and pairs of links 100 15 pivotally connected at their lower ends to the opposite ends of the board and at their upper ends to the upper pairs of lugs 11.

ALVA J. FISHER.
